US0D1020825S

(12) **United States Design Patent** (10) **Patent No.:** **US D1,020,825 S**
(45) **Date of Patent:** **** Apr. 2, 2024**

(54) **HOLE SAW**

(71) Applicant: **Bosen Shao**, Wenzhou (CN)

(72) Inventor: **Bosen Shao**, Wenzhou (CN)

(**) Term: **15 Years**

(21) Appl. No.: **29/921,189**

(22) Filed: **Dec. 15, 2023**

(51) **LOC (14) Cl.** **15-09**

(52) **U.S. Cl.**

USPC **D15/139**

(58) **Field of Classification Search**
